CHARGE FORMING DEVICE

Emil O. Wirth and George P. Lum, South Bend,
Ind., assignors to Bendix Aviation Corporation,
South Bend, Ind., a corporation of Delaware

Application July 20, 1940, Serial No. 346,510

6 Claims. (Cl. 261—23)

This invention relates generally to charge forming devices and particularly to horizontal twin barrel carburetors. Certain of the subject matter disclosed herein is being claimed in our copending continuation in part application Serial No. 437,345, filed April 2, 1942.

Many present day automobiles have extremely low hoods so that little vertical space exists thereunder for the downdraft type of carburetor and its air filter which stand upwardly a considerable distance above the top of the engine. It has become a particularly difficult problem to use a downdraft carburetor on engines having overhead valves where the hood level has been lowered to an extreme degree, engines of this type generally having a greater overall vertical dimension than those of the L-head type.

Another factor that must be taken into consideration in solving the problem of a suitable charge forming device for such present day automobiles is that certain types of engines used therein require a dual type of intake manifold each main conduit of which has its own inlet. The in-line or straight eight-cylinder internal combustion engine is one example of a motor generally using a dual intake manifold though other types of engines also use such a manifold.

In solving the present problem, it is, however, undesirable for many reasons to revert to the updraft type of carburetor. One important reason is that at low engine speeds the velocity of the upwardly moving air current in an updraft carburetor is often insufficient to carry all the fuel particles along with it and as a consequence a substantial portion of the fuel runs backward in the induction passages and escapes from the carburetor. This loss of fuel results in an inadequate fuel mixture particularly at low engine speeds. It is also difficult to obtain satisfactory acceleration from a low speed since it is very nearly impossible to deliver an acceleration pump charge to the carburetor induction passage and have the slow moving stream of air pick up this concentrated fuel discharge and quickly carry it upwardly and into the engine cylinders.

The present invention provides a highly efficient charge forming device for engines of low hooded automobiles which will be within the restricted vertical limits imposed by such automobiles and which is so constructed that fuel particles from the main nozzle will be readily carried along by the air stream in the induction pas-

sage and will not run contrary to the direction of said stream even at low air velocities.

Another object of the invention is to provide a device of this character having means for thoroughly atomizing fuel discharged into the mixture passages by the acceleration pump so that said fuel will also be readily carried along by the air stream therein.

Still another object is to provide a device of this character having means for checking back flow of idling fuel in the passages of the idling system.

It is a further object of the invention to provide a device of this character having a plurality of throttle barrels having their axes or the centers of the outlets arranged in the same horizontal plane and adapted for use with intake manifolds having a plurality of inlets positioned adjacent each other.

The invention is further characterised by a single fuel level control for a plurality of main fuel nozzles, said control being effected by means of hydrostatic pressure acting against a movable member; by means for providing a relatively uniform fuel mixture for the various engine speeds; by highly sensitive means for maintaining a substantially uniform fuel level in the fuel supply chamber; and by means for stabilizing the fuel supply between a plurality of main nozzles deriving economizer fuel from a common economizer source.

Still further objects are the provision in a device of this character of an internal vent for the acceleration jet air break chamber; of an acceleration pump disposed within the fuel reservoir and variable capacity means to compensate for various fuel movements occurring during operative movements of the acceleration pump piston; of means rendering the acceleration pump readily accessible; and stabilizing means for the movable wall member controlling the fuel level.

Further objects and advantages of the invention will be apparent from the following description, taken in connection with the accompanying drawings, in which:

Figure 1 is a vertical section through a charge forming device embodying the invention taken longitudinally of the induction passages on line 1—1 of Figure 2;

Figure 2 is a vertical section through the device taken on line 2—2 of Figure 1;

Figure 3 is a side elevation of the accelerator pump actuating lever taken on line 3—3 of Figure 1;

Figure 4 is a partial vertical section through

the air and mixture passages taken on line 4—4 of Figure 2;

Figure 5 is an elevational view of the flange end of the air passages; and

Figure 6 is a partial vertical section through the cover of the fuel supply chamber showing a modification of the vent for said chamber.

The embodiment of the invention illustrated in the drawings and hereinafter described is a preferred embodiment thereof which may be used with a dual horizontal intake manifold such as the one of special construction disclosed in pending application of Emil O. Wirth for a Fuel supply system, filed July 20, 1940, and bearing Serial No. 346,483. It is to be distinctly understood however that the present invention is not to be limited to the embodiment herein disclosed nor to the type of manifold with which it is preferably used, nor otherwise, except by the appended claims.

Referring more particularly to the drawings, the carburetor disclosed therein is of the horizontal draft, double-barrel type. It includes a body section 10 within which is a fuel supply chamber or reservoir 11, and air born section 12, 25 and a throttle body section 13.

Section 12 forms a horizontal air inlet 14 which is controlled by a choke valve 15 of any suitable construction, manipulated either manually or automatically in the known manner. Posterior to the choke valve the walls of the passage are flared as indicated at 16 and the passage then branches into two horizontal mixture passages 17 controlled by throttle valves 18 mounted on a common shaft 19 which is connected with an accelerator pedal and/or hand control in any well known manner. The mixture passages 17 are positioned in close proximity to each other and their axes including the centers of the outlets 17a are in the same horizontal plane, the outlets of said passages being adapted for registration with corresponding inlets of an intake manifold.

Each passage 17 comprises a small venturi 20 supplied with fuel from a main fuel nozzle 21 and discharging into a larger venturi 22. Each nozzle 21 is received within a bore and secured therein by a threaded plug 23 having a calibrated fuel metering orifice 24, said orifice being below the fuel level L—L in said chamber. Each nozzle 21 is also provided with an air bleed 21a from the air inlet passage 14. Fuel discharged by the main nozzles is readily carried along by the air stream in the mixture passages 17 due to the horizontal position of said passages and horizontal movement of air therein and air at even low velocities will cause the fuel to flow toward the intake manifold and be delivered thereto. It should be noted that the air passages 14 and 17 are at the top of the carburetor and that when attached to an internal combustion engine the device will not extend above the top thereof.

Fuel is supplied to both main nozzles 21 at constant head by means of the constant-level fuel reservoir or chamber 11 which includes a lower portion 11a and upper portion 11b connected by vertical portion 11c. The portion 11a and lower part of 11c constitute the fuel accommodating space. Constant level in the chamber 11 is maintained through hydrostatic pressure acting on a flexible diaphragm 25 which closes the lower end of said chamber. The diaphragm is marginally clamped between a flange 26 on the lower end of the body 10 and a flange 27 about the rim of a cup-shaped bottom cap 28 secured to the body 75

by screws 29. The diaphragm provides a movable wall or member which becomes the effective capacity limiting bottom of the fuel chamber, the capacity of said chamber consequently being variable.

At its underside, the diaphragm 25 has a metal disk 30 with a downturned rounded flange 30a. The disk reinforces or supports the diaphragm over a relatively large central circular portion of its area so that the flexure of the diaphragm occurs primarily in the annular area 31 outside the supported central area. Beneath the diaphragm is a coil spring 32, the upper end of which is received in a shallow recessed washer 33 and the lower end in a similar washer 34. The upper washer is secured between the disk 30 and a lock nut 35, of well known character, received on the threaded depending end of screw 36, a flat disk 37 being interposed between the hexagonal head 38 of screw 36 and the upper surface of the diaphragm. The lower washer 34 is received on a reduced end portion 39 of adjustment screw 40, the washer abutting on a shoulder formed at the base of said reduced portion 39. The spring is centered by the washers 33 and 34 relative to the axis of the diaphragm and reacts between said washers, thereby providing a yielding support for the diaphragm.

Adjustment screw 40 is threaded into a stud 41 depending from the bottom of cap 28, said screw being in axial alignment with the diaphragm 25 and provided with an axial bore 42 therethrough in which is slidably received a depending stem 43 of screw 36, whereby the diaphragm is permitted free vertical operative movement but is supported against axial tilting. A lock nut 44 locks the screw 40 in adjusted position. However, other suitable mechanism may be employed to support and adjust the diaphragm.

About the depending end of screw 40 is an integral annular flange 45 depending from the cup 28. A removable plug 46, pressed into and frictionally held in an annular notch in the free end of flange 45, completes enclosure of a chamber 47. This plug prevents tampering with the adjustment of screw 40 once said adjustment has been made establishing the proper fuel level in the fuel chamber. However, should it become necessary to alter the adjustment of screw 40, the plug 46 may be removed to provide access to said screw 40. The passage 48 provides an air vent between chamber 47 and compartment 75 so that the respective pressures therein will at all times be equalized with respect to each other, thereby preventing establishment of undesirable pressures that might otherwise occur in chamber 47, such as would restrict operative movements of stem 43 in bore 42. It should be noted that the stem 43 fits loosely enough in the bore 42 to substantially eliminate friction with the walls thereof so as to ensure free operative movements of the diaphragm which must necessarily be highly sensitive to even slight variations of hydrostatic pressure within the fuel chamber 11.

The top wall or cover 49 of the fuel chamber has a hollow boss 50 for a pipe connection with a fuel source and within said boss a fuel strainer 51 is disposed for straining out foreign particles from the fuel delivered to the carburetor. A vertically bored stud 52 depends from boss 50 into the upper portion 11b of the fuel chamber, the bore of said stud communicating with the interior of the boss. The vertical bore of the stud 52 is threaded and receives a fuel inlet valve

member 53 having a seat 54 with which a valve 55 cooperates.

A bracket 56 is received on the lower end of the valve member 53 and is secured between the enlarged head 57 of the valve member and the free end of the stud 52. Bracket 56 has an upturned end 58 which is associated with a flattened side 59 of stud 52 to retain the bracket in proper position. Depending arms 60 of the bracket, spaced apart from each other, support a pin 61 on which a valve actuating lever 62 is hinged and downturned end portion 63 of the bracket provides a stop for limiting the valve opening movement of lever 62 by engagement with a projecting end portion 64 of said lever, the valve actuating lever 62 being connected to the valve 55 by a wire 65.

Means operably connecting lever 62 with the diaphragm includes a link 66 pivotally connected at 67 to the lever 62 and at 68 to a diaphragm actuated lever 69. The lever 69 is pivotally mounted on a shaft 70 having its ends fixed in opposite walls of the body 10. The end of lever 69 adjacent the axis of the diaphragm is bifurcated, and the free end of each fork 71 is turned about a pin 72 operably received in an annular groove 73 in an extension 74 of the head 38 of screw 36. Through this connecting means vertical movements of the diaphragm effect opposite vertical movements of the valve 55 for controlling the flow of fuel into the fuel chamber 11. The link 66 is weighted at 66a to diminish or eliminate the unbalance in mass acting on lever 69, the inertia effects of which, resulting from vertical accelerations, might otherwise interfere with the maintenance of the proper fuel level. It will be readily apparent that the right hand half of lever 69 or the lever 62 could be weighted instead of link 66.

The operation of the mechanism for controlling the fuel supply to chamber 11 is as follows: When the chamber is empty spring 32 yieldingly maintains the diaphragm at its upward limit of movement at which position valve 55 is wide open. As fuel, supplied by gravity or pressure or otherwise, enters through the duct in the boss 50 it is discharged past the valve 55 and into the fuel reservoir 11. As the fuel accumulates in the chamber, the hydrostatic pressure of the liquid column operates upon the diaphragm to overcome the resistance of spring 32 causing the diaphragm to be depressed and effecting closing movement of the valve. Accumulation of fuel in the chamber to the desired level will effect complete closing of the valve 55.

To equalize the air pressure on both sides of the diaphragm both the compartment 15 formed by the cap 28 below the diaphragm and the fuel chamber 11 are vented to the air horn passage 14. Venting of compartment 15 to the air horn passage is effected through the respective communicating ducts 16, 17, 18, 19 and 20. The upper portion 11b of the fuel chamber, above the fuel level L—L, vents to duct 18 through vent 81 in the top wall 49, so that the air pressure within the fuel chamber 11 and in compartment 15 is equal to the pressure of the air entering the inlet passage 14. This type of venting above and below the diaphragm is preferred as it tends to balance out the effect of any restriction of the air entering the carburetor, such as occurs with the use of an air cleaner particularly as it becomes clogged with dirt, and produces a more nearly uniform fuel mixture.

In Figure 6, a modified type of venting is illus-

trated and includes an upstanding boss 82 on the cover plate or top wall 49 of the fuel chamber. The upper portion of the fuel chamber is vented to atmosphere through passages 83. A raised central portion 84 of the boss 82 supports a dust cap 85 in spaced relation thereto to permit free movement of air through passages 83, the cap 85 being secured to the raised portion 84 by a screw 86. Should an external vent of this type be used for the fuel chamber the compartment 15 should be similarly vented and a vent to atmosphere (not shown) should be provided in cap 28. While certain types of venting to both sides of the diaphragm have been illustrated and described herein it is to be understood that any other suitable method of venting may be employed.

An annular accelerating well 87 is provided about each nozzle 21 by reduction of a portion of the nozzle at 88 and openings 89 in the nozzle 20 permit fuel to pass from the well into the passage 90 of said nozzle in the well known manner.

Idling fuel for each mixture passage 17 is drawn from the lower end of the acceleration well 87 of the respective nozzles through a lateral passage 91, thence upwardly through an idling tube 92 threaded into the body as at 93, to a point above the normal fuel level L—L (Figure 2) in the carburetor. From the tube 92, the fuel flows inwardly and upwardly through inclined passages 94 and horizontally through passages 95 to idling nozzle 97 (Figure 4) of known construction, discharging adjacent the throttle. A limited quantity of air is bled into the idling fuel for the idling nozzles of the respective mixture passages through orifices 95a communicating with the air horn entrance. Additional air is bled to the idling fuel through continuations 98 of passages 94 which communicate with a cylinder 100 through respective restricted orifices 101 in passages 98 adjacent one end of said cylinder. Air from the air inlet passage 14 reaches the said end of the cylinder through a passage 102 and an opening 103 in end wall 104 of said cylinder. A screen 105 covers opening 103 to filter out foreign matter from air entering the cylinder through opening 103. A piston 106 is reciprocatingly disposed in cylinder 100 and functions as an air valve to control ports 107 of passages 98. Actuation of the piston in a direction to close ports 107 is effected by a compression spring 108 received within a bore 109 in said piston. Opening movement of the piston is effected by suction posterior to the throttle valves communicated by means of duct 112, which 40 communicates with both mixture passages 17, and respective ducts 113, 114, 115, 115a and opening 116a, the latter being through end wall 111 of cylinder 100. During engine idling and low pressure posterior to the throttle valves the piston is moved by manifold suction to the extreme right against the force of spring 108, as shown in Figure 1, at which limit of movement ports 107 are open to permit air to be bled into the idling fuel through said ports, as well as through orifices 95a. Upon a rise of pressure posterior to the throttle, as when said throttle valves are opened to accelerate the engine, the spring urges the piston to the opposite limit of movement and closes said ports 107 thereby cutting off atmospheric pressure through said ports and preventing the back flow of idling fuel through the idling fuel passages that such pressure would otherwise effect in connection with gravity. There will be some suction on the idling nozzle 97 which will tend to draw the idling fuel in the idling passages 45 50 55 60 65 70 75

toward the idling nozzle against back flow due to gravity and suction of the main fuel nozzles. Thus, when the throttle valves are again closed and the idling nozzles come into normal operation, idling fuel is immediately available at said nozzles and a lag in the delivery of idling fuel is prevented such as would occur if the idling fuel passages had been drained or partially drained of fuel. However, other suitable means to reduce or eliminate back flow of fuel in the idle fuel passages may be employed.

The carburetor is provided with an economizer system for supplying supplementary fuel from the reservoir 11 to the main fuel nozzles 21, which includes a spring pressed economizer valve 116, of known construction, vertical passage 120, horizontal passage 121 and branches 122.

It is generally known that an air bled main fuel nozzle has an inherent pulsating flow characteristic of rather high frequency which under normal conditions is so rapid as to have no adverse effect on the operation of the engine. We have found, however, that in dual carburetors, if the two air bled nozzles are interconnected by a passage such as the economizer passage 122, the fluctuations in the delivery from the nozzles will at times be synchronized, each nozzle at least partially feeling the effect of a fluctuation in delivery from the other, and very violent fluctuations in fuel delivery may be experienced. At some speeds, this pulsation in fuel delivery becomes so severe as to cause a deficiency in the total quantity of fuel discharged and results in misfiring. In order to remedy this condition, fuel passages 122 are provided with restricted portions 123 which dampen the fluctuations of the fuel between the nozzles 21. The restricted portions 123 are adjacent each other at the point where passage 121 branches in opposite directions to the accelerator wells of the respective main nozzles. Other suitable means may be employed to prevent fluctuation of fuel between the nozzle, and the invention is not to be confined to the above described means.

Vacuum economizer valve actuating means 126, of well known construction and operation, is provided and is subjected to varying air pressures posterior to the throttle valves. Communication between the air passages 17 posterior to said throttle valves is effected through passages 112, 113, 114, 148, 147 and 146. Upon a rise in air pressure posterior to the throttle, a contact disk 132, secured to the spring pressed flexible diaphragm 134, impinges against valve stem 126, thereby opening the economizer valve.

The economizer valve actuating mechanism comprises a chamber 130 in a plug 131 threaded into a side wall of the fuel chamber, said chamber being subjected to varying air pressures posterior to the throttle valves as will be described hereinafter.

An accelerator pump 136, of known construction, is incorporated in the carburetor, and includes a cylinder 150 formed integrally with the interior wall 10a and open at 152 for communication with the chamber 11, whereby removal of the pump piston may be made. Within the cylinder is disposed the piston comprising a plunger 151 having the usual facing material 157. The plunger is fixed to a piston rod 161 having an enlarged free end portion 162 longitudinally drilled from said free end. An annular flange 163 is provided on the enlarged end member 162 and a diaphragm 164 is secured to said enlarged end by clamping same between the

flange and a washer 165 by turning over the free end of member 162. A marginal portion of the diaphragm 164 is clamped within a diaphragm chamber 167 adjacent the inner end thereof by a cup-shaped nut 168 screwed into said chamber 167, a retaining washer 169 being interposed between the diaphragm and adjacent rim of the nut 168. Removal of nut 168 provides access to the accelerator pump and permits removal of the piston thereof. The diaphragm 164 forms a flexible seal that prevents escape of fuel from the fuel chamber 11 past the piston rod and also permits free operative movements of said piston rod, said diaphragm also provides means whereby the capacity of chamber 167 is varied. It should be noted that the inner end of chamber 167 communicates with the fuel chamber 11 at 167a. An extension 170 is secured to piston rod 161 by pressing milled end 171 of rod 170 into the bore in the enlarged end 162 of said piston rod. The rod 170 extends through an opening 173 in the head of nut 168, the opening 173 being of substantially greater diameter than rod 170 thereby permitting free operative movements thereof. However, any other suitable sealing means may be employed.

It should be noted that the capacity of the cylinder exteriorly of the piston and the capacity of the variable capacity chamber 167 vary inversely of each other. Consequently, the volume of fuel moved by reciprocating action of the piston is compensated for by inverse variation in the capacity of the chamber 167 so that the fuel level in the reservoir is substantially unaffected by the movements of the acceleration pump piston.

Means for actuating the acceleration pump is particularly shown in Figure 3 and comprises a lever 174 pivoted at 175, the free end of which is perforated to pivotally receive laterally turned end portion 177 of rod 170. A lever 178 floats on the pivotal axis 175 of lever 174 and is connected to lever 174 by a spring 179 having its ends attached to lateral arms 180 and 181 of levers 174 and 178, respectively. The levers are normally retained in the aligned position, as shown in Figure 3, by abutment of lug 182 on lever 178 against a laterally turned stop member 183 of lever 174. A link 184, pivoted to the free end of lever 178, is operably connected to the throttle actuating mechanism, not shown, so that the acceleration pump is actuated with opening movement of the throttle valve. Rotation of lever 178, counterclockwise with reference to Figure 3, tensions spring 179, thereby pulling lever 174 in a manner to effect fuel discharging movement to the accelerator pump piston in the well known manner. The accelerator pump operating means herein illustrated and described is preferred although any other suitable means may be used. The pump receives fuel through a check valve 188 and discharges it upon discharge movement of the piston through vertical passage 189, lateral passage 190, vertical passage 191, and horizontal passage 192, the latter forking into two downwardly inclined branches 193, each branch supplying fuel to respective passages 194. Each passage 194 is inclined upwardly and is provided with a restricted orifice 195 from which accelerating fuel is discharged across air break chamber or bore 196 and through the discharge opening 197, the latter being of somewhat larger diameter than the orifice 195 and in axial alignment therewith to permit free flow of the fuel stream therethrough into the mixture passage

17. The accelerating fuel is discharged posterior to the throttle and the direction of discharge is such that slight initial opening of the throttle valve brings said valve into the path of the fuel being discharged, said path being the axial line of the orifice 195 and opening 196. Impingement of the fuel stream upon the valve causes the stream to be broken up and atomized so that same will be carried along by the air stream in the mixture passage 17, and will not settle and collect within said passage 17 nor run contrary to the direction of the air stream even at low air velocities. Passage 189 is provided with a ball check valve 189a in an enlarged portion 189b of said passage, the valve being above the fuel level of chamber 11. The air break 196, separating restricted orifice 195 and opening 197, is interiorly vented to the upper portion 11b of the fuel chamber by means of passages 198, 199 and 200.

It is thought that the invention and many of its attendant advantages will be understood from the foregoing description and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a carburetor having an induction passage including an air inlet, means forming a fuel chamber having an air space above the fuel accommodating portion thereof, a yielding wall member forming a part of the fuel chamber and exposed to hydrostatic pressure of fuel therein, said fuel chamber having a fuel inlet, a valve controlling the inlet, means operably connecting the yielding wall member and valve, said yielding wall member being responsive to hydrostatic pressure of fuel in the chamber, means forming a substantially closed compartment on the outer side of the wall member relative to the fuel chamber, and means whereby the upper portion of the fuel chamber and the compartment are vented to the air inlet.

2. In a carburetor having a pair of induction passages, a fuel reservoir, fuel nozzles adapted to

discharge fuel into respective induction passages, means including fuel metering means for supplying fuel from the reservoir to the nozzles, means for supplying the nozzles with an auxiliary fuel supply from a common source including a fuel passage interconnecting said nozzles posterior to said metering means, and means in said passage for damping fluctuations of fuel flow between the nozzles.

10 3. In a carburetor for an internal combustion engine having a plurality of induction passages, a fuel reservoir, a fuel nozzle for each induction passage receiving fuel from the reservoir, and a conduit having a branch to each of the fuel nozzles for supplying same with an auxiliary supply of fuel, each of said branches having a restriction therein for damping fluctuations of fuel flow in said branches.

4. In a carburetor having a throttle controlled induction passage, means forming a fuel reservoir including a yielding member responsive to hydrostatic pressure of fuel therein, a fuel inlet, a valve for said inlet controlled by the yielding member, a wall forming a chamber on the side of the yielding member opposite the reservoir, a guide projecting outwardly through the wall of said chamber, a stabilizer attached to the yielding member and operably associated with the guide, resilient means reacting between the guide and the yielding member, said guide being adjustable to alter the effectiveness of the resilient means whereby the level of the fuel in the reservoir may be varied, and a second chamber enclosing the projecting end of the guide.

30 5. The invention defined in claim 4 and including a vent between the chambers.

35 6. In a charge forming device having an induction passage controlled by a throttle, means forming a fuel chamber including a yielding wall member responsive to hydrostatic pressure of fuel in said chamber, a valve controlled fuel inlet, means connecting the wall member and the valve, means forming a closed chamber on the outer side of the wall member, and means for venting both chambers to the induction passage.

EMIL O. WIRTH.
GEORGE P. LUM.
